SUCTION CLEANER

Thomas A. Stoner, North Canton, Ohio, assignor
to The Hoover Company, North Canton, Ohio,
a corporation of Ohio

Application December 7, 1939, Serial No. 307,967

5 Claims. (Cl. 183—51)

This invention relates to improvements in suction cleaners in general and more particularly to an improved form of muffler to reduce the operating noise of the cleaner.

An object of the invention is to provide a new and improved suction cleaner. Another object is to provide a new and improved muffler for suction cleaners. A further object is to provide a resonant muffler for attenuating undesirable sound waves, to thereby reduce the noise caused by operating the cleaner. Another object is to provide a resonant muffler that is capable of attenuating sound waves in dirt-laden air. A further object is to provide a resonant muffler that is easily disassembled for removing foreign material from the resonant chambers. Other objects and advantages of the invention will be apparent from the specification and drawings, wherein:

Figure 1 is a side elevational view partly in section illustrating one embodiment of the resonant muffler attached to the exhaust of a suction cleaner;

Figure 2 is a disassembled view of the resonant muffler shown in Figure 1;

Figure 3 is a side elevational view partly in section of another embodiment of the invention;

Figure 4 is a broken exploded perspective view of the muffler shown in Figure 3, and

Figure 5 is a side elevational view, partly in section, of a suction cleaner embodying the invention.

The embodiment of the invention disclosed in Figures 1, 2 and 5 comprises a suction cleaner having a casing 10 provided with a nozzle 5 communicating with a fan chamber 6 having a fan 7 operated by a motor 8 for discharging dirt-laden air through an exhaust passageway 11 into a dust-filtering bag 12.

A resonant muffler, indicated generally at 15, includes a casing composed of two sections 16 and 17, the latter being provided with a conduit 18 having spaced radial walls 19, 20 and 21. The casing section 16 includes a cylindrical shell 13 which encloses the radial walls and is removably secured thereto by a pair of nut and bolt connections 22 pivotally supported on the casing end wall 19 and extending through recesses 23 in a flange 24 on the shell 16. The shell 16 cooperates with the radial walls and the conduit 18 to form resonant chambers 25 and 26 concentric about the conduit 18, the resonant chamber 26 being of less volume since the partition wall 20 is spaced a less distance from the end wall 21 than from the opposite end wall 19.

In order to provide entrances to the resonant

chambers, the conduit 18 is provided with a pair of annularly arranged openings 27 and 28 communicating respectively with the resonant chambers 25 and 26. The cumulated area of the openings 27 and 28 are of a predetermined area with respect to the volumes of their respective resonant chambers 25 and 26, to attenuate sound waves in different bands of frequencies.

The resonant muffler is pivotally connected to 10 the cleaner casing by means of a pair of arms 29 extending from the casing end wall 19 and which are pivotally mounted on a pin 30 supported on spaced arms 31 projecting from a member 32 removably attached to the exhaust flange 9 of the cleaner casing 10 by a pair of bolt and nut connections 33. A torsion spring 34 is incorporated in the hinge and supports part of the weight of the muffler 15 to bias the latter in an upwardly inclined direction. In order to connect the 20 muffler with the exhaust passageway 11 a flexible bellows 35 is removably attached in the opening 36 in the member 32 and the opposite end is detachably mounted in an annular groove in the projecting portion 37 of the conduit 18. The 25 dust-filtering bag 12 is removably supported at its lower end on the muffler casing shell 13 by a clamp 38, the muffler being disposed within the bag 12 which is supported at its upper end by the unshown cleaner handle.

In operation, assume the cleaner is removing dirt from the surface being cleaned. The sound waves produced by operating the suction cleaner are carried by the dirt-laden air through the flexible bellows 35 into the muffler exhaust 18, 35 where the sound waves pass through the entrances 27 and 28 into the resonant chambers 25 and 26 respectively. Due to the relative areas of the entrances 27 and 28 to the volumes of their respective resonant chambers 25 and 26 the latter will function to attenuate the sound waves over predetermined bands of frequencies, whereby the noise produced by the suction cleaner is reduced to a minimum. The dirt-laden air is discharged into the dust bag 12 and the dirt accumulates about the outer wall 13 of the muffler without entering the latter or contacting the flexible bellows 35, whereby the latter remains clean and the flexing thereof is not impaired by the accumulation of dirt. If it is desired to clean the bag 12 the clamp 38 is loosened and the bag removed from the muffler casing.

Any foreign material that collects in the resonant chambers 25 and 26 is removed by slipping the outer shell 13 from the inner casing 17 to thereby uncover annular openings which expose

each resonant chamber, as shown in Figure 2, whereby the foreign matter is easily removed.

Another embodiment of the invention is disclosed in Figures 3 and 4 included in the suction cleaner shown in Figure 5 comprising a casing 10 provided with a nozzle 5, fan chamber 6 and motor 8, which operates a fan 7 to discharge the dirt-laden air removed from the surface being cleaned through an exhaust passageway 11.

A resonant muffler 52 is pivotally connected to the cleaner and includes a casing composed of two sections 53 and 54, the latter having a conduit 55 provided with spaced radially extending walls 56, 57 and 58. The casing section 53 is of truncated conical configuration and encloses the radial walls and is removably connected thereto by means of screws 59 which extend through a flange 60 on the shell 53 and are threaded into apertures 61 on the end wall 58. The shell 53 cooperates with the radial walls and conduit 55 to form a pair of resonant chambers 63 and 64, the latter being of less volume since the partition wall 57 is arranged more closely to the end wall 58 than to the end wall 56. An entrance to each of the resonant chambers 63 and 64 is provided by the openings 65 and 66 respectively in the conduit 55, the openings being substantially circular with the exception of a solid portion 67 in the conduit 55. Each of the entrances is covered by a perforated metal member 68. The entrances 65 and 66 are of pre-determined area with respect to the volume of their respective resonant chambers to thereby attenuate sound waves in different bands of frequencies.

In order to pivotally connect the resonant muffler to the cleaner casing, the muffler casing section 54 is provided with spaced arms 70 pivotally supported on a pin 71 carried in spaced arms 72 on a member 73 removably attached to the cleaner casing 10 by a pair of bolt and nut connections 74. A torsion spring 75 supports part of the weight of the resonant muffler 52 to bias the latter in an upward direction. The muffler conduit 55 is connected to the exhaust passage 11 by a flexible bellows 76 having one end detachably supported in a groove in the member 73 and its opposite end in an annular recess in a projecting portion 77 of the muffler conduit.

A dust filtering bag 80 of paper or the like, has its lower end removably supported in a clamp 81 which is detachably supported on the projecting portion 83 of the muffler conduit 55 by means of a bayonet connection 82. An outer bag 84 of cloth or the like, is arranged about the inner bag 80 and has its lower end removably secured to a flange 85 provided on the member 73 to thereby completely enclose the resonant muffler 52 and flexible bellows 76.

In operation, assume the suction cleaner is discharging dirt-laden air into the paper bag 80. The sound waves produced by the operation of the suction cleaner are carried by the dirt-laden air into the muffler conduit 55 and pass through the entrances 65 and 66 into the resonant chambers 63 and 64. Due to the relation of the areas of the entrances 65 and 66 to the volumes of their respective resonant chambers 63 and 64, the latter function to attenuate sound waves in predetermined bands of frequencies, whereby the noise produced by the suction cleaner is effectively reduced. The dirt laden air is discharged into the paper bag 80 and the foreign material is retained therein to prevent accumulation of dirt about the flexible bellows 76 and thus avoid impairment of flexing of the latter when the bags

80 and 84 are moved with the cleaner handle. The paper bag 80 is easily removed from the muffler conduit 55 by manipulating the clamp 81, and is removed from the outer bag 84 through an unshown opening therein.

If foreign material collects in the resonant chambers 63 and 64 it is easily removed by slipping the shell 53 away from the inner casing 54 to thereby uncover the annular openings to the resonant chambers whereby the latter are easily cleaned.

I claim:

1. In a suction cleaner, a cleaner body having an exhaust passageway for discharging dirt removed from the surface being cleaned, a sound-reducing resonant muffler comprising inner and outer casings, said inner casing having a conduit communicating with said exhaust passageway for conveying the dirt-laden air through said muffler, means cooperating with said inner and outer casings to define a resonant chamber, means defining an opening in said conduit for connecting said resonant chamber with said dirt-laden air stream to attenuate the sound waves in said dirt-laden air stream, a dirt-filtering bag supported by said resonant muffler to receive the dirt-laden air discharged by said muffler, means at one end of said inner casing for connecting said muffler to said cleaner body, and means for removing said outer casing from said inner casing to remove the foreign material in the resonant chamber without disturbing the connection of said dirt bag with said muffler.

2. In a suction cleaner, a cleaner casing having an exhaust passageway through which the suction cleaner expels air laden with dirt and surface litter removed from a surface being cleaned, a bag for filtering the dirt-laden air, a resonant muffler movably attached to said casing for movement between substantially vertical and horizontal positions and formed with a resonant chamber, said muffler having a conduit for conveying the dirt-laden air from said exhaust passageway and opening interiorly into said bag, said resonant muffler being disposed completely within said bag and having a cross-sectional area less than that of said bag so as not to interfere with the passage of air through the walls of said bag, said conduit having perforations for the passage of the sound waves in said dirt-laden air into said resonant chamber to attenuate said sound waves as the dirt-laden air passes through said conduit, characterized in that said suction cleaner forces air, dirt and surface litter through said conduit and past said perforations in all angular positions of said muffler.

3. In a suction cleaner, a cleaner casing having a nozzle, an exhaust passageway and suction creating means for drawing through said nozzle air laden with dirt and surface litter from a surface being cleaned and to force said air, dirt and surface litter through said passageway, a bag for receiving the dirt-laden air from said passageway, a sound-reducing resonant muffler attached to said casing for movement between substantially vertical and horizontal positions and having a resonant chamber and a conduit communicating with said passageway, and said conduit having perforations in its side walls out of alignment with the direction of movement of said air, dirt and surface litter for passage of the sound waves into said resonant chamber to attenuate said sound waves, said suction creating means functioning to force said air, dirt and sur-

face litter through said conduit with sufficient speed as to move said air, dirt and surface litter into said bag in all angular positions of said muffler and prevent the entrance of said dirt and surface litter into said resonant chamber through said perforations.

4. In a suction cleaner, a cleaner casing having an exhaust passageway for discharging the dirt-laden air removed from the surface being cleaned, a bag for receiving the dirt-laden air from said exhaust passageway, a sound-reducing resonant muffler having cooperating removable casing sections forming a resonant chamber and having a conduit communicating with said exhaust passageway to receive and conduct said dirt-laden air to said bag, said conduit having perforations for the passage of the sound waves in said dirt-laden air into said resonant chamber to attenuate said sound waves as the dirt-laden air passes

5 through said conduit into said bag, and means for the separation of said removable muffler casing sections to expose said resonant chamber for the removal of foreign material therein.

5. In a suction cleaner, a cleaner casing having an exhaust passageway for discharging the dirt-laden air removed from the surface being cleaned, a bag for receiving the dirt-laden air, a muffler casing having a conduit communicating with said exhaust passageway to receive and conduct said dirt-laden air to said bag, said conduit communicating with the interior of said muffler casing to form therewith a resonant muffler chamber to attenuate the sound waves in said dirt-laden air as the dirt-laden air passes through said conduit into said bag, and means for exposing said resonant chamber for the removal of foreign material therein.
